[57] CLAIM

The ornamental design for a support stand for beverage containers, as shown and described.

DESCRIPTION

FIG. 1 is a perspective view of a support stand for beverage containers showing my new design;

FIG. 2 is a top plan view thereof;

FIG. 3 is a bottom plan view thereof;

FIG. 4 is a side elevation view thereof, the opposite side being a mirror image thereof;

FIG. 5 is a side elevation view thereof as seen from the right in FIG. 4; and

FIG. 6 is a side elevation view thereof as seen from the left in FIG. 4.
